Des. 203,329
Patented Dec. 28, 1965

203,329

HELMET

Mary G. Fitchko and Michael Hearty Fitchko,
190 N. Roosevelt, Columbus, Ohio

Filed Apr. 26, 1965, Ser. No. 84,955

Term of patent 14 years

(Cl. D3—13)

FIG. 2.

FIG. 1.

FIG. 3.

FIG.5.

FIG.4.

FIG.6.

FIG. 2 is a top plan view thereof;

FIG. 3 is a side elevational view thereof;

FIG. 4 is a front elevational view thereof with the visor in a raised position;

FIG. 5 is a top plan view thereof; and

FIG. 6 is a side elevational view thereof.

We claim:

The ornamental design for a helmet, substantially as shown.
